Primary Examiner — Brett Miller*Assistant Examiner* — Nader Abadir(74) *Attorney, Agent, or Firm* — Jeenam Park(57) **CLAIM**

The ornamental design for a stove, as shown and described.

DESCRIPTION

FIG. 1 is a front, right and top perspective view of a stove, showing my new design;

FIG. 2 is a rear, left and bottom perspective view thereof;

FIG. 3 is a perspective view in the open configuration thereof;

FIG. 4 is a front view of FIG. 1;

FIG. 5 is a rear view thereof;

FIG. 6 is a left side view thereof;

FIG. 7 is a right side view thereof;

FIG. 8 is a top plan view thereof;

FIG. 9 is a bottom plan view thereof; and,

FIG. 10 is an enlarged view of portion of FIG. 1 thereof. The broken lines shown in the drawings illustrate portions of the stove that form no part of the claimed design.

1 Claim, 10 Drawing Sheets(56)
